UNITED STATES PATENT OFFICE.

CHARLES H. BEELER, JR., OF PHILADELPHIA, PENNSYLVANIA, ASSIGNOR TO
DAVID WOLFE BRUCE, OF NEW YORK, N. Y.

DESIGN FOR A FONT OF PRINTING-TYPE.

SPECIFICATION forming part of Design No. 12,694, dated January 17, 1882.

Application filed November 17, 1881. Term of patent 14 years.

To all whom it may concern:

Be it known that I, CHARLES H. BEELER, Jr., (assignor to DAVID WOLFE BRUCE,) of the city and county of Philadelphia, Pennsylvania, 5 have invented and produced a new and original Design for a Font of Printing-Type, of which the following is a specification.

The nature of my design is clearly shown in the accompanying typographic impression, to 10 which reference is made.

The face of the letters, punctuation-marks, and numerals is in thin, solid, black lines, and in plain Roman form, except that in the letters A, B, D, E, F, H, I, J, K, L, M, N, P, R, T, U, 15 V, W, X, Y, and Z the ornamentation of a

small curved line extending from the left of the up-and-down portion of the letter, about centrally, occurs. The shading is placed below and on the right of the face of the letter, and is separated from it by a narrow space. The 20 shading is inclined downward toward the right.

Having now set forth my invention, what I claim as new is—

The design for a font of printing-type, as shown and described.

C. H. BEELER, JR.

In presence of—

JOSEPH J. BROADHURST,
RUDOLPH KOCH.
